UNITED STATES PATENT OFFICE.

WALTER R. PETERSON, OF PARK RIDGE, ILLINOIS, ASSIGNOR TO INTERNATIONAL HARVESTER COMPANY, A CORPORATION OF NEW JERSEY.

DISK SCRAPER FOR HARROWS.

Application filed January 30, 1928. Serial No. 84,819.

This invention relates to scrapers for disk harrows, and is more particularly concerned with improvements in the blades and blade securing devices for such implements.

It is an object of the invention to provide a disk harrow scraper assembly having a novel and advantageous arrangement of its component parts.

Among other objects, the invention is intended to provide a scraper blade constructed of sheet metal so as to promote greater strength in such blades and to facilitate economies of manufacture.

A still further object is to provide a novel form of coupling for use in attaching the scraper blade to its supporting shaft in an advantageous manner.

Other objects will appear as the description proceeds.

An illustrative embodiment of the invention is shown in the accompanying drawings, in which:

Fig. 1 is an elevation of the disk harrow scraper assembly;

Fig. 2 is an elevation taken at right angles to the plane of Fig. 1; and

Fig. 3 is a horizontal section of the illustrative assembly taken on the line 3—3 of Fig. 2;

The illustrative scraper assembly includes a supporting shaft 10 to which a scraper blade 11 is rigidly secured by means of an interposed coupling 12 and a U-bolt 13.

The shaft 10 is herein shown as of square stock material such as is commonly used in implements of the character herein specified. This shaft is supported in a well known manner relative to gangs of earth working disks so as to appropriately support a scraper for each disk in proper operative position.

A lower portion of each scraper blade 11 operates in close proximity to a disk to remove earth which may stick thereto. This part of the blade is the operative part and will be hereinafter referred to as the point 14 or the point portion of the blade. It is constructed of sheet metal of appropriate thickness or gauge to provide adequate strength together with the requisite amount of flexibility.

The point 14 is joined to the heel 15 by a main body portion 16 which has a central longitudinal rib 17 formed therein to adequately strengthen the blade. This rib is

shown as progressively increasing in height from the point of its beginning 18 upwardly of the blade. At its upper extremity, however, its height above the balance of the blade is not great enough to substantially interfere with the bending of the blade at 19 to form the heel 15. Neither is the height of the rib at this point so great as to substantially weaken the structure of the blade at this bend.

The heel 15 is shown as being extended at an obtuse angle to the remainder of the blade, and is formed so that its cross section is similar to the cross section of the main body portion and point of the blade. It thus includes an intermediate portion 20 which is arched upwardly, this portion being shown as a substantial continuation of the rib 17. The arch 20 lies between two flat parts 21 appropriately formed within the same horizontal confines so as to adequately maintain the entire blade in its effective working position, as will be hereinafter explained.

The coupling 12 is formed near its ends with flat surfaces lying within the same horizontal plane. They are adapted to fit tightly against the flat parts 21 of the heel 15 so as to promote advantageous securing of the blade in working position. Between these flat surfaces the coupling 12 is provided with an upwardly cut-away part forming a downwardly facing groove 22 adapted to provide room for the arch or rib 20, which is arranged therein as clearly shown in Fig. 2. This arrangement of heel parts relative to the coupling promotes effective resiliency and elasticity of the blade as a whole, permitting the rib or arch 20 to exercise its full strengthening and bracing effect upon the point 14. Displacement of the blade by unusual resistances encountered in operation will be immediately counteracted by the added elasticity afforded by the rib, and the blade will be returned to its normal position. This result is promoted by the location of the arch or rib 20 whereby it is free from contact with the coupling.

Prevention of any substantial twisting of the heel 15 relative to the coupling 12 is accomplished by the formation of shoulders 23 upon the lower face of the coupling. These shoulders are shown parallel to each other and otherwise so arranged that they

substantially provide a socket for receiving the heel 15. In order that effective securing of the coupling 12 to the shaft 10 may be promoted, the coupling is shown 5 provided with an upwardly facing groove 24 located directly opposite the groove 22. The coupling is thus formed with substantially thickened outer portions 25 with a comparatively thin portion or web 26 connecting them. Consequently, the coupling 10 may be described as I-shaped or as substantially double-concave as to its cross section. Externally of the I-shaped section of the coupling 12, the ends 27 are drilled as indicated at 28 for the reception of the legs 15 of an appropriate securing device such as the U-bolt 13. Appropriate strength is given to these ends by the illustrative lugs 29 to compensate for the removal of material by the drilling of the coupling.

The U-bolt 13 is shown as having its bight located above the shaft 10 with its legs extending downwardly on either side thereof. Each leg passes between a shoulder 25 23 and a corresponding side of the heel 15 which are appropriately grooved, as indicated at 30 and 31, respectively. The coupling, heel, and U-bolt are thus locked against displacement. In effect, each leg of the 30 U-bolt operates as a gib or key to lock the coupling to the scraper blade, as clearly indicated in Fig. 3.

Spaced abutments for the marginal portions of the heel 15 are formed by the burrs 35 32 which are screw-threaded upon the legs of the U-bolt 13 so that they may adequately grip the heel and also bind all of the parts of the illustrative assembly tightly together. The heel forms a substantially A-shaped 40 truss between abutments provided by the shoulders 23 or the burrs 32.

What I claim as my invention, and desire to secure by Letters Patent, is:

1. A scraper assembly for disk harrows 45 comprising a supporting shaft, a U-bolt having its bight lying above said shaft, a scraper blade having a relatively low rib longitudinally centrally thereof, the blade having an angular heel formed with a similar rib, and 50 a double groove coupling interposed between said heel and the shaft, the rib of the heel lying within a groove of said coupling.

2. A scraper assembly for disk harrows comprising a shaft, a ribbed scraper blade supported by said shaft, a coupling having 55 upper and lower grooved surfaces and interposed between said shaft and said blade, and a downwardly opening U-bolt securing all of the above mentioned parts rigidly together.

3. In a device of the class described, a rock shaft, a U-bolt straddling said rock shaft with its bight lying over the upper portion of the rock shaft, a coupling having a depressed mid-portion conforming to the 65 periphery of the rock shaft, the opposite side of the coupling having opposite flat surfaces lying in the same plane and separated by a downwardly opening channel, and a scraper formed of sheet metal having 70 portions held tightly against said surfaces by said U-bolt and an arched portion entering said channel.

4. A disk harrow scraper comprising a supporting shaft, a substantially double concave coupling engaging said supporting shaft, a U-bolt enclosing said supporting shaft and having its legs extending downwardly through the ends of said coupling, a scraper blade having an angular heel centrally arched between flat marginal heel 75 portions, and means for tightly pressing said heel up against said coupling.

5. A one piece scraper for disk harrows comprising a blade, said blade having an angular heel formed with a central arched portion intermediate two co-incidental flat 85 portions, a flat end portion, and a main body portion connecting said heel and end portions, said main body having a centrally 90 arched formation similar to that of said heel and merging therewith.

6. A scraper assembly for disk implements comprising a shaft, a spacing block 95 engaging the shaft and formed with flanges having openings located on opposite sides of the shaft, a scraper blade seated on said flanges and formed with channels registering with said openings, and clamping means in engagement with the shaft and blade 100 having parts fitted in said openings and channels.

In testimony whereof I affix my signature.
WALTER R. PETERSON.
